BRUSH FORMING MACHINE

Curtiss F. Smith, West Hartford, Conn., assignor
to Fuller Brush Company, Hartford, Conn., a
corporation of Connecticut

Application April 3, 1937, Serial No. 134,811

17 Claims. (Cl. 300—2)

My invention relates to the type of machines employed for forming brushes from strips of material within which the bristles are secured and from which they project, and an object of 5 my invention, among others, is the production of a machine of this type that shall be simple in construction and particularly effective in operation.

One form of a machine embodying my invention and in the construction and use of which the objects herein set out, as well as others, may be attained is illustrated in the accompanying drawings in which—

Figure 1 is a view in side elevation of my improved brush forming machine.

Figure 2 is a top plan view of the same.

Figure 3 is a view in section on a plane denoted by the dotted lines 3—3 of Fig. 1.

Figure 4 is a view in section on a plane denoted by the dotted lines 4—4 of Fig. 3.

Figure 5 is a view on enlarged scale illustrating the operation of forming a brush.

Figure 6 is a top plan view illustrating a modification of my invention.

Figure 7 is a view in side elevation of this latter form.

Figure 8 is a view on enlarged scale illustrating the operation of the machine shown in Figs. 6 and 7.

My invention contemplates the formation of brushes of substantially cylindrical shapes by first coiling into indefinite lengths a strip of material within which the bristles are secured and from which they project, which lengths of brush form may be subsequently cut up into suitable pieces such as may be required for any particular purpose, said strip being in the form of a trough composed preferably of metal and within which the bristles are doubled and secured by a pinching action and from the open side of which they project.

A machine embodying my invention and as illustrated in the accompanying drawings comprises a supporting frame 10 which in fact is a plate of any suitable material, preferably metal, having flanges 11 on opposite sides comprising rests to support the frame in an upright position. A hub 12 projects from the front face of the frame to receive a mandrel supporting rod 13 firmly secured to and projecting from the hub to support a mandrel 14, as shown in Figs. 1 and 3 of the drawings. A bearing block 15 is rigidly secured to the frame in any suitable manner and comprises a bearing 16 for the spindle 17 of a guide roller support which comprises

a head 18 secured to the spindle and having a guide rotatably mounted at its outer end. The head 18 is preferably formed in halves applied to the spindle from opposite sides, as shown in Fig. 3 of the drawings of a similar structure which cooperates with said head 18 now to be described. These halves are secured together as by screws, as shown in Fig. 1, and the spindle may be supported in the bearing in any desired manner. Said spindle has a threaded hole in the end opposite the head 18 to receive an adjusting screw 19 held against lengthwise movement in a lug 20 projecting from a flanged extension from the bearing block 15. The guide roller just referred to comprises two members 21 rotatably mounted in the head 18 and relatively angularly disposed as shown by similar guide rollers illustrated in Fig. 3, the cooperating edges of the rollers being shaped to receive a metal strip 22 which is clearly shown in Fig. 5 of the drawings.

The base 23 of another roller supporting spindle is pivotally attached to the frame 10 as by means of a bolt 24 which comprises said pivot, and this base supports, preferably integral therewith, a bearing 25 for a spindle 26 projecting diagonally downward and with its axis adapted to be aligned with the axis of the mandrel 13 and extended across the axis of the mandrel and as shown in Fig. 1 of the drawings. A head 27 for members of a guide roller 28 is secured to the end of the spindle 26, said head and roller being of a construction similar to that just described as to the head 18 and roller 21. An arcuate slot is formed in the base 10 as shown in dotted lines in Fig. 1 of the drawings, a clamping bolt 29 extending through said slot into the base 23 for the purpose of clamping the latter in any desired position, this adjustment being for a purpose to be presently described. The bearings 16 and 25 are split at their outer sides, as shown in Figs. 1 and 2 of the drawings, to receive clamping bolts to secure the spindles 17 and 26 from turning movement, the bolts being loosened to permit the spindles to be rotated for adjustment purposes for a function to be hereinafter described. An adjusting screw 30 is held against lengthwise movement in an ear 31 projecting from the base 23, said screw being threaded in to the end of the spindle 26 for the purpose of adjusting the latter lengthwise in the same manner as described with respect to the spindle 17. A wedge 32 is inserted in a groove in the under side of the base 23, as particularly shown in Fig. 3, this wedge having a slot through which the bolt 24 projects. The

wedge has an ear 33 through which an adjusting screw 34 projects to adjust the wedge and thereby change the position of the spindle 26 for a purpose now to be described.

5 The machine is intended to produce brushes or brush structures of different sizes in diameter, and as shown in full and dotted lines in Fig. 1 of the drawings. When the brush structure is made to closely fit the mandrel the axis 10 of the spindle 26 is in line with and the line of such axis passes laterally through the axis of the mandrel. If a brush structure of larger diameter is to be formed then the angle of the axis of the spindle 26 is changed so that it may be in line with the axial center of the brush structure to be formed.

When a brush is to be formed with the several coils quite close together, as shown in Fig. 5, the axis of the spindle 26 will be disposed as shown in Figs. 1 and 2 of the drawings, the guide rolls 28 being located slightly out of line with and at one side of the guide rolls 21. If the coils are to be located farther apart, then by manipulating the adjusting screw 34 the wedge 32 is outwardly drawn underneath the base 23 with a result that the latter is moved so that the guide rolls 28 are located more out of line with the guide rolls 21. A result will be that the several coils of the brush structure will 30 be located at such distance apart as may be desired, the wedge in fact being used to change the pitch of the spiral brush to be produced.

It will be noted that in these operations the location of the mandrel is not changed as it 35 is intended for support of the formed brush structure only in opposition to the two sets of guide rolls 21-28. The position of the spindle 26, however, is changed in two directions. The brush strip 22 may be fed to the guide rolls 21 40 in any suitable manner, as herein shown feed rolls 35 being employed which rolls are in fact a part of a machine for forming the strip 22. It is not essential, however, that the strip shall be taken directly from the strip making machine as obviously it might be fed to the roll 45 21 by hand or otherwise.

A strip being forced through the space between the mandrel and the rolls 21-28, as by the rolls 35 or otherwise, is curved on an arc 50 imposed by the relative positions of the rolls 21-28 and also their positions relatively to the mandrel 14, and the metal comprising the strip 22 being sufficiently ductile, this arc is maintained throughout the length of the structure 55 formed by the operation of the machine.

That form of the device shown in Figs. 6 to 8 inclusive is much the same as that hereinbefore described, the machine, however, being equipped to produce a brush structure of the form shown in Fig. 8 in which the bristles project from the strip 22 substantially lengthwise of the mandrels rather than crosswise thereof as shown in the structure in Fig. 5, thereby producing a structure in which the bristles assume a somewhat 65 conical form. In this form of the machine the frame comprises a base 36 from which oppositely disposed sides 37 and a front 38 rise to support a table 39. The guiding and forming mechanisms are disposed in horizontal positions rather 70 than in vertical positions as shown in Figures 1 to 4, and the mandrel extends vertically instead of horizontally. For this reason many of the reference numerals applied to Figs. 1 to 4 are employed in connection with Figs. 6 to 8. The 75 hub 12 projects upwardly from the table to sup-

port the mandrel rod 13 which bears the mandrel 14. The bearing block 15 is supported by the table 39 in a horizontal position, the parts mounted on the block being as hereinbefore described. The guide rollers, however, in this form 5 of the device are of different shapes owing to the different manner of presenting the strip thereto, these rollers 40-41 having their peripheries formed to correspond with the shape of the side of the brush strip 22 instead of with the back of said strip as in the other form of 10 the machine. The heads 42-43 for the support of the guide rolls are forked to receive said rollers between the branches of said forks and as shown in Fig. 8.

15 The difference between the two machines having been now set forth a further and detailed description of the machine shown in Figs. 6 to 8 is omitted, as its structure will be readily understood in a comparison with the other form of 20 the machine which bears the same reference characters.

The brush structures formed in this machine may be cut up into as many different lengths as may be desired and embodying as many of the 25 coils as may be wished for. In other structures a single coil may be employed if desired so that the strip from which the bristles project will form a ring the ends of which may be secured together.

30 In accordance with the provisions of the patent statutes I have described the principles of operation of my invention, together with the device which I now consider to represent the best embodiment thereof; but I desire to have it 35 understood that the device shown is only illustrative and that the invention may be carried out by other means and applied to uses other than those above set out.

I claim:

1. A brush making machine including a support for a brush strip comprising a base with bristles projecting therefrom, a guide to engage said base and press said strip against said support as the strip is forced into the space between the guide and support, and a second guide to direct said strip in a circular direction relatively to said support, said guide being positioned relatively to the first mentioned guide to bend and set said strip to a predetermined curvature and to cause movement of said strip in a circular path around said support independently thereof. 45

2. A brush making machine including a support for a brush strip comprising a base with bristles projecting therefrom, a guide to engage said base and press said strip against said support as the strip is forced into the space between the guide and support, and a second guide to engage and direct said strip in a circular direction relatively to said support and out of line with its direction of movement thereto to produce a coil, said guide being positioned relatively to the first mentioned guide to bend and set said strip to a predetermined curvature and to cause movement of said strip in a circular path around said support independently thereof. 55

3. A brush making machine including a support for a brush strip comprising a base with bristles projecting therefrom, a guide roll to engage said base and press said strip against said support as the strip is forced into the space between the guide and support, and a second guide roll to direct said strip in a circular direction away from the first mentioned roll and relatively to said support, said second guide roll being po- 60

65 70 75 80 85 90 95

3. A brush making machine including a support for a brush strip comprising a base with bristles projecting therefrom, a guide roll to engage said base and press said strip against said support as the strip is forced into the space between the guide and support, and a second guide roll to direct said strip in a circular direction away from the first mentioned roll and relatively to said support, said second guide roll being po- 75

- sitioned relatively to the first guide to bend and set said strip to a predetermined curvature and to cause movement of said strip in a circular path around said support independently thereof.
4. A brush making machine including a support for a brush strip comprising a base with bristles projecting therefrom, a guide roll to engage said base and press said strip against said support as the strip is forced into the space between the guide and support, and a second guide roll to engage said strip and direct it in a circular direction relatively to said support and out of line with its direction thereto to produce a coil, said second guide roll being positioned relatively to the first guide to bend and set said strip to a predetermined curvature and to cause movement of said strip in a circular path around said support independently thereof.
5. A brush making machine including a support for a brush strip comprising a base with bristles projecting therefrom, a guide roll shaped to fit said base and press said strip against said support as the strip is forced into the space between the guide and support, and a second guide roll shaped to fit said base and guide said strip in a circular direction relatively to said support, said second guide roll being positioned relatively to the first guide to bend and set said strip to a predetermined curvature and to cause movement of said strip in a circular path around said support independently thereof.
6. A brush making machine including a support for a brush strip comprising a base with bristles projecting therefrom, a guide to engage said base and press said strip against said support as the strip is forced into the space between the guide and support, a second guide to engage said strip and direct it in a circular direction relatively to said support, said second guide being positioned relatively to the first guide to bend and set said strip to a predetermined curvature and to cause movement of said strip in a circular path around said support independently thereof and means for adjustably positioning said second guide to direct said strip out of line with its direction of movement to said support.
7. A brush making machine including a support for a brush strip comprising a base with bristles projecting therefrom, a guide to engage said base to press said strip against said support as the strip is forced into the space between the guide and support, a second guide roll to engage said strip and direct it in a circular direction, said second guide being positioned relatively to the first mentioned guide to bend and set said strip to a predetermined curvature and to cause movement of said strip in a circular path around said support independently thereof, a spindle to support said guide roll, and means for rotatably adjustably positioning said spindle to incline said roll to direct said strip out of line with its direction of movement to said support.
8. A brush making machine including a support for a brush strip comprising a base with bristles projecting therefrom, a guide to engage said base and press said strip against said support as the strip is forced into the space between the guide and support, a spindle, said spindle being mounted in cooperative relation to said support, means for rotatably adjusting said spindle, a head secured to said spindle, and a guide roll rotatably mounted in said head and positioned relatively to said guide to bend and set said guide strip to a predetermined curvature and to cause movement of said strip in a circular path around said support independently thereof, and means for adjusting said spindle in a direction lengthwise of its axis.
9. A brush making machine including a support for a brush strip comprising a base with bristles projecting therefrom, a guide to engage said base and press said strip against said support as the strip is forced into the space between the guide and support, a second guide to engage said strip and direct it in a circular direction relatively to said support, said second guide being positioned relatively to the first mentioned guide to bend and set said strip to a predetermined curvature and to cause movement of said strip in a circular path around said support independently thereof and means for changing the position of the last mentioned guide to change the radius of the wire and, thereby vary the diameter of the coil formed in said machine.
10. A brush making machine including a support for a brush strip comprising a base with bristles projecting therefrom, a guide to engage said base and press said strip against said support as the strip is forced into the space between the guide and support, a second guide to direct said strip in a circular direction relatively to said support, said second guide being positioned relatively to the first mentioned guide to bend and set said strip to a predetermined curvature and to cause movement of said strip in a circular path around said support independently thereof and means for changing the position of the last mentioned guide by moving it in one direction relatively to said support, and another means for changing its position by movement in another direction relatively to said support.
11. A brush making machine including a support for a brush strip comprising a base with bristles projecting therefrom, a guide to engage said base and press said strip against said support as the strip is forced into the space between the guide and support, a head supported in cooperative relation to said support, a second guide supported by said head to engage said strip and direct it in a circular direction relatively to said support, said second guide being positioned relatively to the first mentioned guide to bend and set said strip to a predetermined curvature and to cause movement of said strip in a circular path around said support independently thereof, means for rotatably adjusting said head on an axis passing laterally through the axis of said support, and means for adjusting its position relatively to said support.
12. A brush making machine including a support for a brush strip comprising a base with bristles projecting therefrom, a guide to engage said base and press said strip against said support as the strip is forced into the space between the guide and support, a spindle supported in cooperative relation to said support, means for rotatably adjustably positioning said spindle on an axis passing laterally through the axis of said support, a head secured to said spindle, a guide roll mounted in said head to engage said strip and direct it in a circular direction, said guide roll being positioned relatively to the first mentioned guide to bend and set said strip to a predetermined curvature and to cause movement of said strip in a circular path around said support independently thereof, and means for adjusting said spindle in a direction lengthwise of its axis.
13. A brush making machine including a support for a brush strip comprising a base with

- 5   bristles projecting therefrom, a guide to engage said base and press said strip against said support as the strip is forced into the space between the guide and support, a pivotally mounted base, a spindle supported in bearings on said base, means for adjusting the position of said spindle lengthwise of said bearings, means for retaining said spindle in different positions of adjustment, a head secured to said spindle, means for rotatably adjustably positioning said spindle on an axis passing laterally through the axis of said support, and a guide roll rotatably mounted in said head to engage said strip and guide it in a circular direction relatively to said support, said guide roll being positioned relatively to the first mentioned guide to bend and set said strip to a predetermined curvature and to cause movement of said strip in a circular path around said support independently thereof.
- 10   14. A brush making machine including a support for a brush strip comprising a base with bristles projecting therefrom, a guide to engage said base and press said strip against said support, as the strip is forced into the space between the guide and support, a guide to engage said strip and direct it in a circular direction relatively to said support, means for adjusting the position of the last mentioned guide to change the direction of movement of said strip and thereby produce a series of laterally spaced convolutions in said strip, and means for adjusting the position of said last mentioned guide to vary the space between said convolutions.
- 15   15. A brush making machine including a support for a brush strip comprising a base with bristles projecting therefrom, a guide to engage said base and press said strip against said support as the strip is forced into the space between the guide and support, a guide roll to engage
- 20   said strip, said roll being positioned to direct said strip in a circular direction relatively to said support and also in a lateral direction to produce a series of convolutions in said strip, means for adjustably varying the position of said roll to vary the space between said convolutions, and means for adjusting the position of said roll to accord with the formation of said convolutions.
- 25   16. A brush making machine including a supporting frame, a mandrel projecting from said frame to support a brush strip comprising a base with bristles projecting therefrom, a guide to engage said base and press said strip against said mandrel as the strip is forced into the space between the guide and mandrel, a guide supporting base adjustably pivotally mounted on said frame, a guide supporting slide lengthwise adjustably mounted on said base, a spindle rotatably adjustably mounted on said slide, a head secured to said spindle, a grooved guide roller rotatably mounted in said head, and means for axially adjusting said spindle.
- 30   17. A brush making machine including a supporting frame, a mandrel projecting from said frame for the support of a brush strip comprising a base with bristles projecting therefrom, a guide roller shaped to fit the side of the base of said strip and support it against the mandrel as the strip is forced into the space between the roller and mandrel, a guide supporting base adjustably pivotally mounted on said frame, a spindle mounted in bearings on said base, means for rotatably adjusting said spindle, a head secured to said spindle, a roller rotatably mounted in said head and shaped to fit the side of the base of said strip, and means for axially adjusting said spindle.

CURTISS F. SMITH.
